(57)

CLAIM

The ornamental design for the lid organizer, as shown and as described.

DESCRIPTION

FIG. 1 is a front perspective view of the lid organizer showing our new design;

FIG. 2 is a partial enlarged view of section A shown in FIG. 1;

FIG. 3 is a partial enlarged view of Section B shown in FIG. 1;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof; and,

FIG. 10 is a front view of the lid organizer shown in an accompanying storage case showing exemplary use of the lid organizer.

The surface pattern shown in broken lines forms no part of the claims. The dash-dot-dot-dash broken lines in FIGS. 2-3 depict a cut line and form no part of the claim. The broken lines showing a case in FIG. 10 depict environment and form no part of the claim. The broken lines shown crossing claimed surfaces depict stitching and form no part of the claim. All other broken lines depict portions of the article and form no part of the claimed design.
